(57) **CLAIM**

The ornamental design for a cutting tool holder, as shown and described.

DESCRIPTION

FIG. 1 is a front view of a cutting tool holder in accordance with an embodiment of the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof;

FIG. 8 is an enlarged view of portion 8 of FIG. 7; and,

FIG. 9 shows a cutting tool holder in an environment of use thereof.

The broken lines shown in the drawings represent portions of the cutting tool holder that form no part of the claimed design. The dashed-dot-dashed lines indicate a boundary between the claimed portions and the unclaimed portions of the design.
